Fig. 3

Fig. 4

Fig. 5

Fig. 6

Fig. 7

FIG. 1 is a front perspective view of a sewing machine frame showing my new design;

FIG. 2 is a rear perspective view;

FIG. 3 is a front elevational view;

FIG. 4 is a rear elevational view;

FIG. 5 is a top plan view;

FIG. 6 is an end elevational view looking from the left of FIG. 3; and

FIG. 7 is an end elevational view looking from the right of FIG. 3; and

FIG. 8 is an end elevational view looking from the right of FIG. 3.

I claim:

The ornamental design for a sewing machine frame or similar article, substantially as shown.
